FLAT KNITTING FRAME

Max Nebel, Chemnitz, Germany

Application November 18, 1938, Serial No. 241,256
In Germany June 18, 1935

3 Claims. (Cl. 66—91)

This invention relates to a device for producing two-threaded knit fabric having sinker loops of different length, as plush-loop fabric, on a flat knitting machine.

5 In order to produce plush-loop fabric, and particularly the kind provided with plush loops above each sinker loop, it has been proposed to fit both the jack and dividing sinkers with a plush throat arranged above and in front of the ground-thread throat. As it is not possible after two threads have been drawn out at different lengths to divide also at different lengths by means of dividing sinkers equipped with plush throats, this proposal is limited to flat knitting frames 10 having no dividing sinkers. To produce plush-loop fabric having plush loops above each dividing sinker loop on a flat knitting frame equipped with both jack and dividing sinkers, as a Cotton frame, it is known to divide the plush loops, which 15 are longer than the ground-thread loops, by means of the upper edge of auxiliary sinkers moving during the sinking and dividing operations from the front between the frame needles and being positioned in front of the dividing sinkers, in downward direction by the descending frame needles. In the known type of flat or Cotton frame the second thread can be sunk into longer loops than the ground thread by 20 means of jack sinkers having a plush throat, so that the plush thread is drawn out horizontally like the ground thread, but longer than the latter. The dividing sinkers of this type of machine possess either one throat or two throats separated by a nib, the upper throat being located 25 exactly vertically, or approximately so, above the lower ground thread throat. In the latter instance, too, it is therefore necessary to divide downwardly.

To permit dividing of the longer plush loops 30 against the elastic needle shanks in the regular manner without employing an inelastic firm edge as suggested by the older proposals according to which dividing is performed by means of the upper edge of rigid auxiliary sinkers or of a nib provided on the dividing sinkers, the invention 35 provides for sinking longer loops from the second thread not against the shank of the needle but against the front edge of auxiliary sinkers one of which is arranged during the sinking operation 40 in front of each dividing sinker between the frame needles and at so low a level between them in the direction of sinking that, compared with the loops formed from the ground thread, the length of the loops sunk from the plush thread, 45 measured from the front edge of the auxiliary

sinkers behind the needles to the plush throat of the sinkers in front of the needles, is twice the extent to which the sinker loops from the second thread are to be longer than the sinker loops sunk from the ground thread. Furthermore, the 5 distance between the front edge of the auxiliary sinkers and the needle shank is approximately the same as that between the sinking point in the plush throat and the sinking point in the ground thread throat of the jack sinkers, and the 10 auxiliary sinkers, during the dividing operation, advance in front of the dividing sinkers and move out of the needle row when the dividing sinkers enter between the needles for division and thereby pass the loops drawn out longer behind the 15 needles through them, so that the longer drawn out plush thread is divided against the needle shank to form loops that are longer than those sunk from the ground thread.

Flat knitting frames are known, in which a 20 second thread is sunk longer than the first against the edge at the free end of one or more auxiliary sinkers, passing from the front through the needle row, instead of against the shank of the needle. In this case, however, the thread 25 drawn out longer is kept away from the needle shank until the frame needles move down to the press, and the longer loop does not pass under the needle point, but is cast off toward the rear side of the fabric for the purpose of producing 30 plated patterns. The loop portion drawn out longer is therefore not worked into a loop and not divided as according to the invention to form sinker loops that are longer than the sinker loops 35 of the ground fabric. The use of auxiliary sinkers passing from the front through the needle row for the purpose of sinking longer loops is known also in the production of single-threaded common hosiery on flat knitting frames and serves 40 for working sinker loops of different width for patterning purposes.

One form of the invention together with the loop-forming tools of a Cotton frame is shown in the accompanying drawing, in which

Figure 1 shows the position of the loop-forming tools during the sinking operation;

Fig. 2 shows the position of the loop-forming tools during the dividing operation;

Fig. 3 shows the position while the frame needles move into putting-on position;

Fig. 4 is a top view of the loop-forming tools shown in Fig. 1;

Fig. 5 is a top view of the loop-forming tools in the position shown in Fig. 2; and

Fig. 6 shows the sinking position according 55

to Fig. 1 with differently shaped jack and dividing sinkers of known type.

A jack sinker 6 and a dividing sinker 7 are disposed in known manner in the sinker head 4.

- 5 The jack sinker 6 is equipped with a plush-thread throat 6^a having an approximately vertical lower edge 6^a and, arranged below and in the rear thereof, a ground-thread throat 6^b.

The dividing sinker 7 possesses a ground-thread throat 7^b and, above and in front thereof, a plush-thread throat 7^c having an approximately vertical lower edge 7^a. Between the frame needles 9 auxiliary sinkers 11, one in front of every dividing sinker 7, are arranged during the sinking operation. The upper edge 11^a is located slightly above the top edge of the jack sinker and the lower edge 11^b lies about level with the ground-thread throat 6^b. The free end of the auxiliary sinkers 11 has a vertical or almost vertical edge 11^c connecting below with the pointed portion 11^d having a horizontal upper edge 11^e and a rearwardly and downwardly inclined lower edge 11^f. The end 11^e of the pointed portion 11^d and the upper edge 11^a are approximately on a level with the corners 6^c, 7^c of the plush throat. During the sinking operation, Fig. 1, the auxiliary sinkers 11 are so positioned between the frame needles that the second thread 3^a is sunk by the advancing jack sinkers 6 not at the needle shank but 20 at the almost vertical edge 11^c at the free end of the auxiliary sinkers 11. The edge 11^c of the auxiliary sinkers is located at approximately the same distance to the rear of the needle shank as the throat 6^c of the jack sinker 6 is positioned in 25 front of the ground-thread throat 6^b.

The ground thread 1^a guided from the inclined lower edge of the pointed portion 11^d of the auxiliary sinkers 11 during advance of the jack sinker on the ground-thread throat 6^b is sunk at the 40 needle shank in the usual manner. The position of the thread is shown clearly in Fig. 4.

When the dividing sinkers 7 advance for the dividing operation, the auxiliary sinkers 11, always slightly in front of the dividing sinkers, 45 move out of the needle row and into the position shown in Fig. 2, so that the thread 3^a is held between the edges 11^e, 11^c of the auxiliary sinkers 11 and the inclined upper edge of the plush throat 7^c of the dividing sinkers 7 until the 50 dividing operation is completed. The excess thread of the loop formed from the thread 3^a cannot be displaced therefore while the auxiliary sinkers move out of the needle row and cannot jump out of the plush throat 7^c. The 55 dividing operation is carried out so that the excess portion of the loop formed of the thread 3^a, which extends from the needle shank to the edge 11^c of the auxiliary sinkers 11, is engaged by the throat 7^c of the dividing sinkers 7, passed 60 during advance of the latter through the needle row, and formed into a loop in the direction of the needle shank, the loop having the same length as the loops suspended in the plush throats 6^c of the jack sinkers 6, as indicated in Fig. 5.

65 Fig. 3 shows the position of the loop-forming tools during the descent of the frame needles and indicates that the loop formed of the second thread, for instance a plush loop, can easily slide off from the almost vertical edge.

70 In the event of small differences in length between the ground thread loops and the loops formed of the second thread the throat 6^c or 7^c for the second thread is preferably provided with a vertical or almost vertical lower edge. When 75 the differences in length are, however, consid-

erable, as for instance in the production of loop-plush fabric, a nib 6^h or 7^h having a downward sloping upper edge (Fig. 6) may be arranged between the two superposed throats of the jack and dividing sinkers in known manner.

It is immaterial whether the thread guides are in their usual high position or whether the outlet of the ground thread guide is at the level of the ground thread throat and the guide for the second thread has its outlet on a level with the upper throat.

I claim:

1. A flat knitting frame, comprising frame needles, jack sinkers and dividing sinkers, each of said sinkers having a ground thread throat, a second throat located in front of the first throat, the lower throat of said sinkers sinking and dividing the ground thread and the upper throat sinking and dividing a plush thread, auxiliary sinkers arranged in a bar in front of the needle row, means for moving the auxiliary sinkers in the direction of the needles through the needle row towards the dividing sinkers in such manner that the plush thread is drawn out longer than the ground thread against the front edge of the auxiliary sinkers and not against the needle shanks.

2. A flat knitting frame, comprising frame needles, jack sinkers and dividing sinkers, each of said sinkers having a ground thread throat, a second throat located in front of the first throat, the lower throat of said sinkers sinking and dividing the ground thread and the upper throat sinking and dividing a plush thread, auxiliary sinkers arranged in a bar in front of the needle row, means for moving the auxiliary sinkers in the direction of the needles through the needle row towards the dividing sinkers in such manner that the plush thread is drawn out longer than the ground thread against the front edge of the auxiliary sinkers and not against the needle shanks, one of said auxiliary sinkers being arranged in front of each dividing sinker, and means for actuating the auxiliary sinkers in such manner that the auxiliary sinkers during the sinking operation are positioned between the frame needles and enter the needle row to such an extent in sinking direction that, compared with the loops formed from the ground thread, the length of the loops sunk from the upper or plush thread, measured from the front edge of the auxiliary sinkers behind the needles to the plush throat of the sinkers in front of the needles, is twice the extent to which the sinker loops from the second thread are to be longer than the sinker loops sunk from the ground thread, that the distance between the front edge of the auxiliary sinkers and the needle shank is approximately the same as that between the sinking point in the plush throat and the sinking point in the ground thread throat of the jack sinkers, and that the auxiliary sinkers during the dividing operation advance in front of the dividing sinkers and move out of the needle row when the dividing sinkers enter between the needles for division and thereby pass the loops drawn out longer behind the needles through them, so that the longer drawn out plush thread is divided against the needle shanks to form loops that are longer than those sunk from the ground thread.

3. In a flat knitting frame, sinkers, auxiliary sinkers disposed in a bar arranged in front of the needle row and each auxiliary sinker having a free end, means for moving said bar and auxiliary sinkers toward the needles and sinkers and

into the needle row and out of it so as to cause the upper or plush thread to be sunk and divided by the sinkers against the free end of the auxiliary sinkers, a vertical edge serving as sinking edge at the free end of each auxiliary sinker, and a pointed portion provided at the lower end

of said sinking edge and directed against the needles and sinkers, said pointed portion having a horizontal upper edge and a lower edge sloping downwardly from the free end.

5
MAX NEBEL.
